SHELL CARTON

Oscar Eggebrecht, Wausau, Wis., assignor to
 Marathon Paper Mills Company, Rothschild,
 Wis., a corporation of Wisconsin

Application October 19, 1942, Serial No. 462,691

2 Claims. (Cl. 229—27)

This invention relates to a carton formed from a single blank adapted for packaging articles such as cartridges and the like.

The packaging and shipping of cartridges and also various fragile articles has presented for a long time very serious problems in preventing accidents occurring during shipment which might cause loss or damage. According to the present invention, a carton is formed from a single blank which is provided with receiving portions for snugly and securely retaining a plurality of articles packaged in a single carton so that they will be securely retained in position and will not come in contact with each other during shipment thereby preventing damage or explosion of cartridges or breakage of fragile articles which may be packaged in the carton.

Further details of the construction will be apparent from the following specification and drawings wherein:

Figure 1 is a plan view of the blank from which the carton is formed.

Figure 2 is a perspective view of the folded carton formed from the blank shown in Figure 1, the carton being shown in partially flat folded condition.

Figure 3 is a plan view of the fully collapsed and flattened carton.

Figure 4 is a perspective view illustrating the first step in setting up the carton, and

Figure 5 is a perspective view of the fully set up and sealed carton containing the articles to be packaged.

Referring to the drawings, Figure 1 illustrates a single blank made of any suitable sheet material, such as cardboard and the like, suitably cut and scored to provide a rear panel 20, a front panel 31, a bottom panel 22, and a cover 21. Retaining panel 27 is hingedly connected to rear panel 20 along score line 41. Retaining panel 27 is provided with suitably spaced locking tongues 8 and 9 and opposing the base of these locking tongues cut score lines 6 and 7 are provided coinciding with score line 41 in order to render the base portions of the locking tongues 8 and 9 more flexible for easy insertion of the locking tongues in receiving slits. The cover 21 is hingedly connected to rear panel 20 along score line 1. The cover, if desired, may be provided with any suitable end flaps or locking tongues for locking same to the body of the carton. However, in this construction no such means are provided as the cover 21 is merely sealed by means of an adhesive tape 50 as shown in Figure

5, after the contents are placed in the set-up carton.

The bottom panel 22 is hingedly connected to rear wall 20 along score line 2. The bottom panel is provided with end flaps 28 and 29 which are hingedly connected to bottom panel 22 along score lines 12 and 13, respectively. The end flaps 28 and 29 are also separated from the adjacent panels 30 and 27 along cut and score lines 11 and 10, respectively. A front auxiliary panel 23 is hingedly connected to the lower edge of the bottom panel 22 along score line 3. An article-retaining panel 24 is hingedly connected to the panel 23 along score line 4. The panel 24 may be provided with a series of circular cut-out openings 26, for example, which are adapted to snugly receive cartridges, or cut out in any desired contour to conform and snugly receive any other articles desired to be packaged in the carton. It is to be understood that any other suitable cut-out portions may be provided in panel 24 depending upon the article or articles which are to be packaged in the carton. Panel 24 may be retained in a plane parallel to the bottom panel, but if desired may be retained in any suitable position, depending upon the positioning of sustaining panel 25.

Hingedly attached to panel 24 is a sustaining panel 25 adapted to be adhesively attached to the rear wall 20 or to be engaged therewith in any suitable manner. If desired, panel 25 may be made of sufficient length so that it will extend to the bottom panel 22 when the carton is set up, and thereby provide sufficient support for the article-receiving panel 24 without necessarily being glued to the rear wall 20.

Side wall 30 is hingedly connected to the rear wall 20 along score line 40. The front wall 31 is hingedly connected to the side panel 30 along score line 45. The second side wall panel 32 is hingedly connected to the front panel 31 along score line 46. The side panel 32 is provided with suitable slits 17 and 18 which as shown in Figure 1 are T-shaped in order to receive the locking tongues 8 and 9 therein. The bottom of panel 32 is preferably cut along a beveled line 19 as shown in Figure 1 in order to avoid any frictional engagement at this point when the carton is set up.

In forming a carton from the blank as previously described, panel 22 and the adjacent hingedly connected panels 23, 24 and 25 which form an extension hingedly connected to the bottom panel, are folded upon the remainder of the blank along score lines 2, 4, and 5 in the rela-

tion shown in Figure 2, and the sustaining panel 25 is adhesively attached by glue or any other suitable means to the rear panel 20. Front panel 31 and the attached panel 32 are then folded over upon the body of the carton along score line 15 so as to assume the position indicated in Figures 2 and 3. The cartons are shipped in this condition to the user.

In setting up the carton, the bottom panel 22 is folded at right angles to the rear panel 20 which automatically brings the front auxiliary panel 23 and panel 24 at right angles to each other into the position as shown in Figure 4. End flaps 28 and 29 are then folded at right angles to the bottom panel 22. The articles to be packaged are then positioned within the cut-out portions 26 and the front panel 31 is then brought around into face to face contact with the front auxiliary panel 23 by hinging panel 31 on score line 15. Side panel 32 is then folded over on score line 16 to overlap flap 29 and is retained in locked position by inserting the tongue portions 8 and 9 within slits 17 and 18. The final package then has the appearance as shown in Figure 5. In order to retain the cover 21 into position it is adhesively secured by means of a piece of tape 50 as shown in Figure 5.

It will be apparent from the foregoing description that the carton produced according to the present invention is of extremely simple construction and very easily and conveniently set up from flat condition. A minimum of carton stock is necessary in forming this carton and production of same requires very simple equipment in view of the fact that only a single panel 25 is glued to the body of the carton itself. No special machinery or equipment is necessary in setting up the carton. Furthermore when the contents are to be used the carton is easily opened by merely releasing the cover and the contents are instantly made available and can be removed from the article-retaining panel.

It is to be understood that any changes and modifications may be made in the carton construction herein disclosed, and it is intended to include such modifications within the scope of the appended claims.

I claim:

1. A collapsible carton formed from a single blank comprising a rear panel, a side panel hing-

edly connected to one longitudinal side edge of said rear panel, a front panel hingedly connected to said side panel, a second side panel hingedly connected to said front panel, a retaining panel hingedly connected to the second longitudinal side edge of said rear panel adapted to be engaged with said second side panel, a cover hingedly connected to the upper edge of said rear panel, a bottom panel hingedly connected to the lower edge of said rear panel, end flaps hingedly connected to said bottom panel extending in operative position as a strut across the entire width of the carton in contact with the said front and rear panels, and an article retaining extension hingedly connected to the bottom panel consisting of in succession a front auxiliary panel adapted to engage the inner face of the front panel, an article-retaining panel extending from the front to rear panel having the same dimensions as the bottom panel, and a sustaining panel 10 adhered to the rear panel, all said panels being integrally hinged along suitably spaced fold lines.

2. A collapsible carton formed from a single blank comprising a rear panel, a side panel hingedly connected to one side edge of said rear panel, a front panel hingedly connected to said side panel, a second side panel hingedly connected to said front panel, said second side panel being provided with spaced slits for receiving locking tongues, a retaining panel hingedly connected to the second side edge of said rear panel, said retaining panel being provided with spaced locking tongues for insertion in the said spaced slits in the said second side panel, a cover 25 hingedly connected to the upper edge of said rear panel, a bottom panel hingedly connected to the lower edge of said rear panel, end flaps hingedly connected to said bottom panel extending in operative position as a strut across the entire width of the carton in contact with the said front and rear panels, and an article retaining extension hingedly connected to the bottom panel consisting of in succession a front auxiliary panel 30 adapted to engage the inner face of the front panel, an article-retaining panel extending from the front to rear panel having the same dimensions as the bottom panel, and a sustaining panel adhered to the rear panel, all said panels being integrally hinged along suitably spaced fold lines.

OSCAR EGGBRECHT.
